PLAYGROUND FERRIS WHEEL

Dewey D. Boyd, 3813 Donna Circle,
North Highlands, Calif.

Filed May 19, 1964, Ser. No. 80,048

Term of patent 14 years

(Cl. D34—5)

FIGURE 1 is a perspective view of a playground Ferris wheel showing my new design;

FIGURE 2 is a front elevational view thereof on a reduced scale; and

FIGURE 3 is a side elevational view with the Ferris wheel disposed in a horizontal position in relation to the frame.

I claim:

The ornamental design for playground Ferris wheel, as shown and described.
